UNITED STATES PATENT OFFICE.

JAMES A. NOBLE, OF HOOSICK FALLS, NEW YORK, ASSIGNOR TO THE NOBLE & WOOD MACHINE COMPANY, OF HOOSICK FALLS, NEW YORK, A CORPORATION OF NEW YORK.

PAPER-MAKING MACHINERY.

969,800.

Specification of Letters Patent. Patented Sept. 13, 1910.

Application filed May 12, 1909. Serial No. 495,467.

To all whom it may concern:

Be it known that I, JAMES A. NOBLE, a citizen of the United States, residing at Hoosick Falls, in the county of Rensselaer 5 and State of New York, have invented certain new and useful Improvements in Paper-Making Machinery, of which the following is a specification.

My invention relates to paper making machinery, and the object of my invention is to provide an improvement on a Jordan engine plug, whereby the bars on a plug shall be held positively in position, and when necessary to remove them it may be done expeditiously and when new bars are placed in position they will be held there as firmly as theretofore, together with such other elements and combinations as are hereinafter more particularly described and claimed. I 15 accomplish these objects by means of the mechanism illustrated in the accompanying drawings, in which:

Figure 1 is an end elevation. Fig. 2 is a section. Fig. 3 is a longitudinal section of 20 a plug provided with my invention.

Similar letters refer to similar parts throughout the several views.

In Jordan engine plugs the great weakness and objectionable and troublesome feature is the means for securing the bars at the small end of the plug. The wrought iron hoop ordinarily used is shrunk on hot; this has to be removed periodically to replace the worn bars and woods with new ones, and being done in the paper mill, this ring is liable not to be shrunk on again perfectly tight, either through carelessness or ignorance, and a large repair bill ensues. This wrought iron hoop also is liable to stretch under the great stress exerted at 30 this point, with the same result described above. To take the place of this wrought iron hoop I construct a cast steel ring, A, with the inner edge, B, of the flange, C, which fits on the end of the plug, D, of an 40 outwardly flaring form, shown in Fig. 2, so that the diameter of the ring from the outer end of the inner edge of the flange, C, is greater than the diameter of the ring from 45 the point where the flange joins the main body of the ring, and I so construct the

ends of the bars, E, and the plug, D, that there shall be provided a shoulder, F, having its contour formed to correspond with the inner edge, B, of the flange, C, in such 55 a manner that as the ring, A, is forced on to the end of the plug, the bars, E, will be engaged by the inner edge, B, of the flange, C, and will act as a wedge thereupon.

I may fasten the ring in place by means 60 of non-corrosive screws, G, which pass through, preferably, elongated slots, g. I, preferably, place a flange, H, on the ring, A, which will extend at least flush with the heads of the screws, G, to prevent the catching and winding of any substance upon the heads of the screws.

The object of making the opening, g, for the screws, G elongated is in order to, if desired, in replacing the ring to move it so 70 that it shall not engage with the bars, E, in the same place as such engagement was made before the removal of the ring, thus preventing undue wearing of the ring in certain places.

When my ring has been drawn onto the plug it cannot become loose unintentionally, and after removal, no skill or special care is required to replace it in as secure a manner as when it was first put on.

What I claim as my invention and desire to secure by Letters Patent is:

The combination of a disk provided with a series of elongated slots therethrough; a flange on said disk flaring outwardly therefrom; a Jordan engine plug provided with a series of bars; shoulders on said bars at the small end of said plug, so arranged and connected up that said flange may be driven onto the said shoulders on said bars and hold them tightly in position on the plug; a series of non-corrosive screws extending through said elongated slots in the disk for the purpose of holding the disk in position on the end of the plug.

In testimony whereof I have affixed my signature in presence of two witnesses.

JAMES A. NOBLE.

Witnesses:
